UNITED STATES PATENT OFFICE.

EDWARD J. OYSTON, OF CHICAGO, ILLINOIS.

LOOSE-LEAF-BINDER POST.

1,241,008.

Specification of Letters Patent. Patented Sept. 25, 1917.

Application filed March 31, 1917. Serial No. 158,890.

To all whom it may concern:

Be it known that I, EDWARD J. OYSTON, a citizen of the United States, and a resident of the city of Chicago, county of Cook, and 5 State of Illinois, have invented certain new and useful Improvements in Loose-Leaf-Binder Posts, of which the following is a specification.

My invention relates to improvements in 10 loose leaf binding devices and more particularly to posts employed in devices of this character.

The object of my invention is the production of a loose leaf binding device which will 15 be of durable and economical construction, one in which the posts will be of a sectional nature, permitting of ready and expeditious expansion or contraction of the same to accommodate any number of leaves, and in 20 which, when a book has been completed, the posts may be readily and easily removed without disturbing the leaves or covers of the book, so as to permit of the insertion of fastening or sealing members of less cost.

25 Other objects will appear hereinafter.

The invention consists in the combinations and arrangements of parts hereinafter described and claimed.

The invention will be best understood by 30 reference to the accompanying drawing, forming a part of this specification, and in which,

Figure 1 is a perspective view of a loose leaf binder embodying the invention,

35 Fig. 2 is an enlarged section through one of the posts of the binder, and

Fig. 3 is a central section through one of the sections of the posts.

The preferred form of construction as 40 illustrated in the drawings comprises posts, each of which is formed of a plurality of identical tubular sections 1. Each of said sections is formed with an externally threaded reduced lower end 2, the upper end there- 45 of being of an internal diameter correspond- ing with that of the external diameter of the end 2, said upper end being provided with an internal thread 3. The opening or passage through each section 1 is reduced 50 at its lower end and internally threaded as at 4.

The posts thus formed are designed for 55 employment in connection with covers 5 and 6, said covers being provided at their rear- ward edges with elongated metallic bars 7 and 8, respectively, with which said covers

are hingedly connected, as will be readily understood. The bar 8 is formed with threaded openings 9 adapted for engagement by the lower end 2 of any one of the 60 post sections 1. The bar 7 is formed with openings 10 through which the upper ends of the posts loosely pass. Each post is formed of as many sections as desired, the sections being readily and easily connected 65 by threading the lower end 2 of one section into the upper end 3 of the next lower section. In this manner it will be seen that the posts may be made as long or short as desired to accommodate the number of 70 sheets desired to be placed in the binder.

The upper cover of the binder is locked in position by means of caps 11 which are adapted to fit loosely over the upper ends of the uppermost post sections 1. Each cap is 75 provided with a medial screw 12 which is adapted for engagement with the threads 4 in the lower end of the uppermost post section, the same being adapted to extend also into engagement with the threads 4 in the 80 upper end of the lower section. Each cap is knurled as seen to facilitate manual rotation of the same, the telescoping of the cap with the upper end of the post permitting of adjustment of the cap into secure engagement 85 with the detachable or upper cover of the binder. By extending the screw 12 the entire length of the upper section of the post and so as to engage with the threads 4 of the lower post section, said screw will serve 90 to reinforce the joint between the post sections, and thus aid in the production of a device possessing great strength and rigidity. To facilitate rotation of the post sections in attaching or detaching the same, 95 lateral openings 13 are provided with which a key or pointed tool may be engaged, as will be readily understood.

By forming each section of each post of a tubular character, when a binder is completed and ready to be stored away, the caps 11 may be removed and a wire or other permanent sealing element may be inserted through each post. After a sealing member has thus been inserted through each post, 100 the latter is detached by unthreading the same from the bar 8, and slipping the post upwardly through the opening 10 in bar 7, thus completely detaching the same. After 105 this has been done, the ends of the wire or sealing element are secured together, thus 110 serving to effectually bind the loose leaves

together with a much cheaper form of construction and permitting the posts to be used in connection with another binder. The tubular character of the post, it will thus be seen tends to economy which amounts to considerable in large establishments where many records are kept in loose leaf binders.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a loose leaf binding device, a post comprising a plurality of tubular sections each having its lower end reduced and threaded, the upper end of each section having a threaded opening adapted for engagement by the reduced lower end of the next higher section; a cap adapted to engage loosely over the upper end of any one of

said sections; and a medial screw on said cap, the lower end of the opening in each section being reduced and threaded for engagement by said screw, substantially as described.

2. In a loose leaf binding device, a post comprising a plurality of tubular sections each having its lower end reduced and threaded, the upper end of each section having a threaded opening adapted for engagement by the reduced lower end of the next higher section; a cap adapted to engage loosely over the upper end of any one of said sections; and a medial screw on said cap, the lower end of the opening in each section being reduced and threaded for engagement by said screw, said screw being of a length to adapt the same for passage entirely through one section into engagement with the threads of the next lower section, substantially as described.

In testimony whereof I have signed my name to this specification in the presence of two subscribing witnesses.

EDWARD J. OYSTON.
